DESIGN.

H. C. BASCOM.

PARLOR COOKING STOVE.

No. 15,674.

Patented Dec. 30, 1884.

UNITED STATES PATENT OFFICE.

H. CLAY BASCOM, OF TROY, NEW YORK.

DESIGN FOR A PARLOR COOKING-STOVE.

SPECIFICATION forming part of Design No. 15,674, dated December 30, 1884.

Application filed October 20, 1884. Term of patent 7 years.

To all whom it may concern:

Be it known that I, H. CLAY BASCOM, a citizen of the United States, residing in the city of Troy, in the county of Rensselaer and State 5 of New York, have invented and produced a new and original Design for Parlor Cooking-Stoves, of which the following is a specification, reference being had to the accompanying cut, print, or engraving of a stove having 10 said design.

This design embraces several new and distinct parts and combinations of parts which go to make up the whole design, as hereinabove specified.

15 The vase on the stove is not a part of this design. One distinctive part is the shape and ornamentation of the cover A, consisting of the swelling top part, a, the inclined open-work portion b, having the series of alternating large and small apertures, bordered by the 20 series of alternating small and larger ornamental corrugations c, and the convexly-curved lower portion, d, having the series of ornaments e along its lower border. Another 25 part is the shape and ornamentation of the upper end door or raised panel, F, consisting of the border-moldings h, meeting at the top in right angles, the four corner ornaments i, and the central ornament, j. Another part 30 is the shape and ornamentation of the lower end door or panel, G, consisting of the border-moldings k in the form of a rectangle with rounded-corners, the raised panel-surface l, enclosed by said moldings, and the corner ornaments, m. Another part is the shape and 35 ornamentation of the panel-plate H, consisting of the four outwardly-projecting parts n, the four intermediate convexly-curved outer edges, o, the central cruciform ornament, p, and the 40 incut ornamental figures q, in combination with the door or panel G, having the aforesaid parts k l m, shaped as shown in the accompanying engraving. Another part is the shape and ornamentation of the stove-body, consisting 45 of the quadrilateral top plate, J, having rounded corners, the plane border u, and cor-

rugated beading v, the front plate, E, having the upright parts f f', and intermediate parts, f'' and g, and the lateral scallop-edged border-moldings w, the end plate, K, having the lower 50 portion wider than the upper part, conformed to the edge of the front plate, and formed with the lateral scallop-edged border-moldings x, and the quadrilateral bottom plate, L, having rounded corners, the plane border y, 55 and the corrugated beading z.

The whole design embraces the shape and ornamentation of the cover A, top plate, J, the front consisting of the parts B C D E, the doors or panels F and G, panel-plate H, end 60 plate, K, and bottom plate, L, whether the legs I, having the ornamental parts r r' s s' s' s' t, shall or shall not be added.

I claim as new—

1. In a design for a stove, the shape and ornamentation of the cover A, consisting of the parts a b c d e, as set forth. 65
2. In a design for a stove, the shape and ornamentation of the door or panel F, consisting of the parts h i j, as shown and described. 70
3. In a design for a stove, the shape and ornamentation of the door or panel G, consisting of the parts k l m, as shown and described.
4. In a design for a stove, the shape and ornamentation of the panel-plate H, consisting 75 of the parts n o p q, in combination with the door or panel G, having the parts k l m, as shown and described.

5. In a design for a stove, the shape and ornamentation of the body, consisting of the 80 parts J E K L, as shown and described.

6. The design for a stove, consisting of the parts A J B C D E F G H K L, shaped and ornamented as set forth.

In testimony whereof I hereunto set my hand, 85 in the presence of two subscribing witnesses, this 17th day of October, 1884.

H. CLAY BASCOM.

Witnesses:

CHARLES H. BENEDICT,
JAMES A. GILMAN.
